UNITED STATES PATENT OFFICE.

HENRY A. STEBER, OF UTICA, NEW YORK.

MOLD FOR CONCRETE.

No. 853,837.

Specification of Letters Patent.

Patented May 14, 1907.

Application filed November 22, 1906. Serial No. 344,609.

To all whom it may concern:

Be it known that I, HENRY A. STEBER, a citizen of the United States, residing at Utica, in the county of Oneida and State of New York, have invented certain new and useful Improvements in Molds for Concrete; and I do hereby declare the following to be a full, clear, and exact description of the invention, such as will enable others skilled in the art 5 to which it appertains to make and use the same.

This invention relates to improvements in molds, and particularly to molds for plastic material.

15 The invention comprises the production of a mold that is particularly adapted for forming concrete blocks according to the wet system, the mold being provided with sides and partitions or core pieces.

20 The invention further comprises a mold having sides, ends adapted to engage said sides, and core pieces positioned between said sides and formed in a plurality of parts for easy removal when one of said sides have 25 been removed.

The object in view is the production of a mold that is provided with core means that is easily removed after the concrete has hardened in the mold.

30 Another object in view is the production of a mold in which a core is provided formed of a plurality of parts that may be adjusted to form any desired shape or block.

A still further object in view is the production 35 of a mold having core pieces formed in a plurality of parts, the various parts being interchangeable and being adapted to be secured in the mold in various positions for forming various shaped blocks, the core being adapted to be removed after one side of the mold has been first removed.

In the accompanying drawings:—Figure 1 shows a perspective view of the preferred embodiment of my invention, the end pieces 45 being removed. Fig. 2 shows a perspective view of a mold embodying the features of the present invention, one side and one end being removed to better disclose the invention. Fig. 3 is a side elevation of a mold 50 embodying the features of the present invention, one side and the ends being removed. Fig. 4 is a view similar to Fig. 3, except that the core pieces are arranged to form a different shaped block. Fig. 5 is a side eleva-

tion of a mold embodying the features of the 55 present invention, one side and the ends being removed, the core being so positioned as to form a double L-shaped block. Fig. 6 is a side elevation of a mold embodying the features of the present invention in a slightly 60 modified form, one side and the ends being removed to better disclose the invention. Fig. 7 is a side elevation of one side of a mold formed according to the present invention, the same showing a slightly modified form of 65 apertures for accommodating the securing means for the cores. Fig. 8 is a fragmentary view in side elevation of a mold made according to the present invention, but having the cores thereof made and positioned in a 70 slightly modified way. Fig. 9 shows a group of molds and means for securing the same together. Fig. 10 is a perspective view of the securing means disclosed in Fig. 9. Fig. 11 is a slightly modified form of means 75 for holding any desired number of molds in position. Fig. 12 is a top plan view of an impression stamp or die used in connection with the present invention. Fig. 13 is a section through Fig. 12 on line 13—13. Fig. 14 80 is a section through Fig. 12 on line 14—14. Fig. 15 is a top plan view of a slightly modified form of an impression stamp or die used in connection with the mold forming a part of the present invention. Fig. 16 is a section 85 through Fig. 15 on line 16—16. Fig. 17 is a section through Fig. 15 on line 17—17. Fig. 18 is a top plan view of another modified form of an impression stamp or die used in connection with the mold forming a part of 90 the present invention. Fig. 19 is a section through Fig. 18 on line 19—19. Fig. 20 is a section through Fig. 18 on line 20—20. Fig. 21, is a plan view of another slightly modified form of an impression stamp or die forming 95 a part of the present invention. Fig. 22 is a section through Fig. 21 on line 22—22. Fig. 23 is a plan view of another form of an impression stamp or die forming a part of the present invention. Fig. 24 is a section 100 through Fig. 23 on line 24—24.

In the manufacture of artificial stones it has been found desirable in many instances to mix the compound into a homogeneous mass and tamp or force the same into molds 105 and after the same has thus received a proper shape it is adapted to be removed from the mold, or usually the mold from it, and is then

placed at a convenient place to set. In the production of artificial stone by this method, molds of considerable strength are required and in view of this requirement it has been found desirable in some instances to mix the mass from which the stone is to be formed into a substantial liquid state and pour into a mold of any desirable construction. Molds of this character need not be very strong, as they simply are required to sustain the weight of the material and are not required to sustain heavy pressures as when tamping the matter in place. It is to this class of inventions of molds that use substantially liquid matter for forming artificial stones that the present invention relates. In the production of a mold for forming artificial stones according to this method commonly known as the "wet system," I provide a mold having sides 1 and 2, and end pieces 3 and 4. The sides 1 and 2 are formed with apertures 5—5 and 6—6 which are adapted to accommodate securing means as lugs 7 and 8. Enlarged openings are also formed in the side members 1 and 2 as 9 and 10 which are so positioned as to have the openings 5 and 6 positioned around the same. The side members 1 and 2 are also provided with notched portions 11—11 and 12—12 for accommodating securing means as lugs 13—13 and 14—14. Grooves 15—15 and 16—16 are preferably formed in the side members 1 and 2 and connect the apertures 11—11 and 12—12, but said grooves are not a necessity, and may be omitted if desired.

Positioned between the side members or plates 1 and 2 are a plurality of core members or plates which are adapted to be securely held in place by the lugs 7 and 8 engaging the respective apertures 5—5 and 6—6. The core plates 17, 18, 19 and 20 when positioned as shown in Figs. 1 and 2 of the drawings are adapted to form a T-shaped block as will be clearly evident.

It will be observed that the core members or plates are beveled at 21 and 22 for forming a sharp corner. In some instances I have found it desirable to equally bevel the core plates on each side as clearly seen in Fig. 3 of the drawings. This will produce a flattened corner instead of an acute corner. By thus beveling the corners it assists in more easily removing the core plates or members from contact with the block after the same has been formed.

It will be observed that the apertures 5 and 6 and the projections 7 and 8 are so arranged that the core members 17, 18, 19 and 20 may be interchanged as may be desired, and may also be placed in any position for forming various shaped blocks. In Fig. 4 of the drawings will be seen how the plate 19 may be positioned to form a continuation of the plate 17. By arranging the plates in this manner 65 an L-shaped block is secured without chang-

ing the mold and by simply readjusting the cores that are already in use.

In Fig. 5 will be seen a slightly modified form of a core plate, as 23, which is adapted to fit in the apertures 5—5 and 6—6 in connection with the plates 18 and 20 so as to form a substantially double L-shaped block. In this form I preferably form both ends of the plate 23 with beveled portions on each side to register with the beveled portions of the plates 18 and 20 so as to form a somewhat rounded or beveled corner in the L of the block.

In Fig. 6 will be seen a slightly modified form of end plates which are bent inward at 24 and 25 for forming an offset portion in the ends of the block that is to be made. Positioned within the apertures 5—5 are core plates or members 26, 27, 28 and 29, while in the apertures 6—6 are positioned core plates 30, 31, 32 and 33. The core plates 26, 27, 28 and 29 are all made of the same shape and have provided beveled portions 34 and 35 on their ends for forming a substantially rounded or beveled corner in the hollow or core portion of the block that is to be formed.

It will be observed that plates 26 and 28 are so positioned as to have their beveled portions 34 and 35 facing outward and engaging the block, while the members 27 and 29 have their beveled portions 34 and 35 facing inward and out of engagement with the block. The members 30, 31, 32 and 33 are formed similar to the members 26, 27, 28 and 29, and have their beveled portions 36 and 37 facing in a similar manner to the beveled portions 34 and 35. By thus providing beveled portions for the core members the same may be easily removed after the side plates 1 and 2 have been removed. The plates 27 and 29 and 31 and 32 are first removed after the side members 1 and 2 have been removed, then the other core plates are also removed. In this way a core is formed in a block in which the core plates are easily and quickly removed without injuring in the least the block, as the beveled portions of the members 27 and 29, as will be clearly seen in Fig. 6 of the drawings, may be removed without in the least molesting the block. After they have been removed the remaining members also may be removed without liability of breaking the block.

Sometimes it is desirable to make a larger beveled portion in the block than the beveled portions 34 and 35 will form. When it is desired to make a large beveled portion, the core plates are made with beveled portions 38 and 39 as clearly seen in Fig. 8 of the drawings. The core plates as seen in Fig. 8 of the drawings, are all made of the same size so that when they are placed in position with the beveled portions 38 and 39 facing outward the beveled portions of the respec-

tive plates will be in alinement and thus form a beveled corner in the block of twice the size as will be formed by the beveled portions 34 and 35. When it is desired to remove the blocks from the mold the side members 1 and 2 are first removed and one of the core plates is removed, as clearly seen in dotted lines in Fig. 8, then the remaining core plates will either collapse or be easily removed in case they stick to the block.

In Fig. 7 will be seen a slightly modified form of apertures as 5'-5' and 6'-6' for accommodating the securing lugs 7-7- and 8-8. The apertures 5'-5' and 6'-6' are arranged in similar relation and position to the apertures 5-5 and 6-6 so as to accommodate the various core plates in their various positions when used to form various shaped blocks.

In assembling the mold forming the present invention, one of the sides is held in position and the end members or plates 3 and 4 are placed so as to engage the apertures 11 and 12 and the grooves 15 and 16. The securing members 7-7- and 8-8 of the various core plates desired to be used are then inserted in the respective apertures 5 and 6 in the member 1. Then the other side member or plate 2 is placed in position so that the other lugs 7 and 8 engage the apertures 5 and 6 in the plate 2, and the end members 3 and 4 also engage the slot and apertures formed in the end of the member 2. The mold is then provided with a clamping means as 40 for holding the same. In practical operation usually a number of the molds are placed together as clearly seen in Fig. 9, and then clamped together by the clamping means 40. Suitable blocks as 41 are preferably used between each mold so as to more firmly hold the sides 1 and 2 always in proper position. As will be evident the tie-rods or members 42 and 43 of the tying means 40 are adapted to pass through the apertures 9 and 10 in the sides of the molds and thus avoid passing through the block. A suitable tensioning device as a clamping nut 44 is provided for each of the rods 42 and 43 so as to always firmly clasp the various molds together.

After the molds have been clamped together either singly or in a series as seen in Fig. 9, the same is placed upon a pallet or if desired a sand bed either smooth or having a prepared configuration thereon and the substantially liquid matter is poured into the molds. Being in a liquid form the matter will run to all parts of the mold and will take the shape of the sand upon which the mold is positioned. From this it will be observed that a mold formed according to the present invention has only the sides ends and core plates and no top or bottom, but uses a sand bed or the pallet as the bottom.

In some instances it has been found desirable to use a framework as 45, as clearly seen

in Fig. 11 of the drawings. In this case the frame or housing 45 is completely filled with molds, and is preferably provided with the spacing blocks 41. A suitable tensioning device, as a set screw 46, is provided at one end of the frame 45 for firmly holding the molds in proper position.

I have described two specific means of a similar nature for holding molds together formed according to my invention, but I wish it understood that I consider myself at liberty to use any form of securing means that is adapted to accomplish the purposes desired, and that I do not consider myself limited to the specific form of clamping means.

My invention is particularly intended for use in making artificial stones according to the "wet system," but it will be evident that certain forms of blocks may be made with equal advantage according to the "dry system." When it is desired to make a T-shaped block, an L-shaped block, or the like, the dry system may be used and the material tamped or pressed into position in the usual manner. When using the dry system, of course, it will be evident that the molds must be made considerably heavier and stronger than when using simply the "wet system." By thus constructing a mold according to the present invention, blocks of a plurality of forms may be formed by a simple system of core plates according to the "wet system" that have not heretofore been made according to the "dry system" without more complicated and multipartite molds. The molds then may be used if desired in producing blocks according to the dry system, but in a simpler form. It will be thus seen that molds formed according to my invention are adapted for making artificial stone according to either system, provided the molds are made sufficiently strong, and the equal adaptation of the mold for either system and forming of the various shaped blocks forms important features in the present invention.

In connection with the mold proper, I use various forms of impression plates or dies for forming the face of the block in various shapes for use in various purposes. In some instances, I place an impression plate or a die upon the surface of a block that is being formed so as to form any configuration that may be desired. The impression plate when thus placed upon the matter being formed into a block will sink downward into the mass and force the surface of the block into the proper form. Sometimes I find it desirable in making the various configurations for the surface of the block being formed to use a framework. The framework is simply placed upon the block that is being formed and composition similar to that of which the block is formed is placed within the frame

and is adapted to contact with the material of the block. The matter added in this way is sufficiently wet as to be formed integral with the block proper, but is held in a predetermined shape by the frame.

Referring more particularly to Fig. 12 of the drawings, a frame 47 is provided, which is adapted to be placed upon the block that is being formed in the mold. The frame 47 is provided with an opening 48 into which matter is placed that is desired to be formed integral with the block, the opening in the frame forming a configuration. From Fig. 13 it will be seen that the inner walls 49—49 of the frame 47 are beveled so as to easily remove the frame after the block has set. The ends are also beveled at 50—50 in a similar manner to the side walls 49—49.

Referring to Figs. 15, 16 and 17, a slightly modified form of frame 51 is shown in which a plurality of openings, as 52 is provided for forming a panel configuration.

Referring more particularly to Figs. 18, 19 and 20 there will be seen another slightly modified form of a frame 53. A comparatively large opening 54 is provided in one end of the frame 53 and two comparatively small openings 55 are formed in the end opposite to 54. In all the various modifications of frame, as shown in Figs. 12, 15 and 18, the walls of the various openings are beveled as seen at 49 and 50 so as to easily remove the various frames after the block has set.

In Figs. 21 and 22 will be seen another slightly modified form of impression plate. The impression plate 56 is adapted to be placed upon the surface of the block that is being formed, and form ridges or columns thereon. Blocks made with a facing formed by the impression plate 56 are especially adapted for use as belting blocks, but also may be used in any other place that may be desired.

In Figs. 22, 23 and 24 will be seen another slightly modified form of impression plate 57 or die in which a rosette or the like is formed so that when the die or plate is placed upon the surface of the block it will form an impression thereon according to the impression contained in the impression plate 57.

In the form of impression plate shown in Figs. 21 and 23, I preferably place a layer of dryer material than is formerly placed in the mold so as to accommodate the weight of the impression plates. The dry matter thus placed upon the surface of the block must be sufficiently wet to form integral with the remaining part of the block when the same sets. I preferably use the coating just described, but it will be evident I may delay the placing of the impression plates upon the block until the same has begun to set. After the same has begun to set, it will sustain the weight of the impression

plates so that by either means any desired configuration may be formed in the block by the impression plates.

It will be observed that the impression plates shown in Figs. 21 and 23 will form configurations in the block that is being formed while the frame shown in Figs. 12, 15 and 18 will form configurations upon and projecting slightly from the block that is being formed. In the one instance the configuration is made from the matter already in the mold, while in the other the configuration is added matter. By thus providing various forms of frame and impression plates any desired configuration may be made either in the form of small columns, fancy configurations, or in fact any arrangement and combination of configurations as may be desired.

I claim:—

1. A mold, comprising walls and ends and a core formed of a plurality of transposable members.

2. A mold, comprising removable sides and ends, and a core positioned in a plane perpendicular to the sides and formed of a plurality of independent transposable members.

3. A mold, comprising bodily and independently removable sides and ends, a core mounted between the sides and supported thereby said core being adapted to be transposed for forming various shaped blocks, and means for securing the mold together.

4. A mold comprising a pair of sides formed with notches in the ends thereof, end members formed with projections that are adapted to engage the notches in said sides, and a core formed of a plurality of transposable parts positioned between said sides and engaged by said sides for holding the same in any desired position.

5. A mold comprising side and end members, a core positioned between said side and end members, said core comprising a plurality of interchangeable parts formed with projecting lugs for engaging said side members, and also formed with beveled portions for permitting easy removal of said core, and means for holding said sides and core in position.

6. In a mold having ends and sides, a core formed of a plurality of members means for individually supporting said members at both ends, said supporting means being of identical construction.

7. A mold comprising sides and ends, said sides being of identical construction and formed with series of apertures therein, means for holding said sides and ends together, and a core formed in parts positioned between said sides, said core being formed with means for engaging some of said apertures in said sides and adapted to being shifted among the series of apertures to vary the shape of the block.

8. In a device of the character described, a core formed of a plurality of separate and independent plates, each plate having individual integral means formed thereon to engage the sides for its own support independent of all other members of the core, said plates being adapted to be separately removed.
9. A mold comprising removable sides and ends, means for securing the same together, and a laterally positioned core formed in parts, said core being formed with lugs for engaging said sides, said lugs being so positioned as to permit the shifting of the parts for varying the shape of the core.
10. A mold comprising removable sides and ends, said sides formed with apertures therein, and grooves near each end thereof, a plurality of core plates positioned between the said sides, means formed integral with said core plates for engaging the apertures in said sides and means for holding said sides together said grooves holding said ends in proper position.
11. A mold comprising removable end and side members, said side members being provided with grooves near each end thereof, a plurality of collapsible core plates positioned between said side members and removably secured thereto, said core plates being adapted to be removed by being collapsed, and means for holding said side members and core in position said grooves being adapted to hold said ends in position.
12. A mold comprising sides and ends, means for securing the same together, and a core positioned between said sides formed with a plurality of members, said members being adapted to be independently remov-
- able, said member being also formed with beveled portions for forming a beveled corner 40 in the block.
13. A device of the character described, comprising a mold with bodily removable sides, a core member secured between said sides, said core comprising a plurality of 45 parts, and means passing longitudinally through said sides and the hollow of the core member for holding said mold in operative position the said holding means being at all times out of contact with the block being 50 formed.
14. In a device of the character described, comprising a mold having perforated and notched side members, plates having extensions formed thereon, said extensions being 55 adapted to engage the notches in said side members, and plates formed with lugs thereon positioned between said side members for forming a core, said lugs engaging said perforations for holding the core in position. 60
15. A device of the character described, comprising a mold having perforated and notched sides, end members formed with extensions, said extensions adapted to engage the notches in said sides, and a plurality of 65 plates of identical construction positioned between said sides and adapted to engage said perforations, said plates being adapted to be varied in position for forming a plurality of different shaped blocks. 70

In testimony whereof I affix my signature in presence of two witnesses.

HENRY A. STEBER.
